UNITED STATES PATENT OFFICE

167,942

SILVERWARE PLACEMAT

Maurice W. Jones, Baytown, Tex.

Application June 30, 1952, Serial No. 20,416

Term of patent 14 years

(Cl. D44—29)

To all whom it may concern:

Be it known that I, Maurice W. Jones, a citizen of the United States of America residing at Baytown, Harris County, State of Texas, have invented a new, original, and ornamental Design for Silverware Placemat, of which the following is a specification, reference being had to the accompanying drawing, forming a part hereof.

Fig. 1 is a perspective view of a silverware placemat showing my new design.

Fig. 2 is a perspective view of the rear side of the silverware placemat, and

Fig. 3 is an end view thereof.

I claim:

The ornamental design of a silverware placemat, substantially as shown.

MAURICE W. JONES
